UNITED STATES PATENT OFFICE

171,467

BROOCH OR SIMILAR ARTICLE

Raymonde Semensohn, New York, N. Y., assignor to Marcel Boucher et Cie, New York, N. Y., a partnership consisting of Marcel Boucher and Jeanne Boucher

Application July 3, 1953, Serial No. 25,793

Term of patent 3½ years

(Cl. D45—19)

To all whom it may concern:

Be it known that I, Raymonde Semensohn, a citizen of the French Republic, residing at 1120 Bergen Street, in the city of New York, county of Kings, and State of New York, have invented a new, original, and ornamental Design for a Brooch or Similar Article, reference being had to the accompanying drawing, forming part thereof.

In said drawing:

Fig. 1 is a front view of a brooch or similar article, showing my new design.

Fig. 2 is a top view of the same.

Fig. 3 is a side view of the same.

I claim:
The ornamental design for a brooch or similar article, as shown.

RAYMONDE SEMENSOHN.
